SPRING BOLT MECHANISM

Monte E. Hover and Wilhelm M. Remarque,
Los Angeles County, Calif.

Application March 24, 1939, Serial No. 263,898

8 Claims. (Cl. 292—180)

Our invention relates in general to spring bolt mechanisms, and more particularly to such mechanisms which may be operated by hand, without the use of keys, or other auxiliary means.

It is an object of our invention to provide a spring bolt mechanism which is simple in construction and operation, and positive in action.

It is another object of our invention to provide such a spring bolt which is both locked and unlocked with a push of one finger, and which, because of its simplicity and compactness, adapts itself to many and varied uses.

It is also an object of our invention to provide such a spring bolt that may be manufactured in quantity and at a cost such as to permit its being sold at a low price.

These and other objects of our invention will become apparent from the following description of a preferred form thereof, and from the drawing illustrating that form, in which:

Fig. 1 is a cross-sectional view of the bolt in locked position, as it may be applied to a window sash,

Fig. 2 is a cross-sectional view of the bolt, showing the first step in unlocking it,

Fig. 3 is a cross-sectional view of the bolt, showing the second step in unlocking it.

Fig. 4 is a cross-sectional view of the bolt in unlocked position,

Fig. 5 is a front view of the bolt as it appears installed, and

Fig. 6 is a cross-sectional view taken at 6—6 in Fig. 1.

Referring now to the drawing, and particularly to Fig. 1 thereof, the numeral 10 indicates a cylindrical housing which is preferably of a generally circular shape, partially closed at its rear end by a constriction 11 having a centrally-disposed outwardly-extending boss 12. A face plate 13, attached to the front end of the housing 10, partially closes that end and also provides a convenient means of fastening the mechanism to the member in which it is to be mounted. An aperture 14, in the face plate 13 and concentric with the axis of the housing 10, permits the insertion of one's finger into the housing 10 to operate the bolt. A plunger 15 is slidably mounted within the housing 10 and projects into the boss 12 at all times, and beyond the latter when the bolt is in locking position. A fixed collar 16, attached near the front end of the plunger 15, is of approximately the same diameter as the inside diameter of the housing 10, the collar and boss 12 cooperating to provide guiding means to hold the plunger co-axial with the housing at all times.

At the front end of the plunger 15 is an enlarged head 17 which is of a small enough diameter to pass through the opening 14 in the face plate 13 without binding or catching the operator's fingernail, and is preferably provided with a slightly concave outer face to aid in preventing a finger from slipping off of it. Between the fixed collar 16 and the plunger head 17 is located a floating collar 18, slidably mounted on the spindle portion of the plunger 15 and urged towards the head 17 by a relatively weak coil spring 19. The floating collar 18 is very slightly smaller than the inside diameter of the housing 10, and is cut away or recessed on its rear face to permit the coil spring 19 to be completely enclosed by it when the floating collar is urged against the fixed collar 16. A second and more powerful coil spring 20 is located within the housing 10 in back of the fixed collar 16 and bears against the latter and the constriction 11 of the housing, urging the two apart.

Along one side of the housing 10, shown in the drawing as the top, we prefer to provide an offset portion 21, lengthwise of the housing and parallel to its axis. The offset 21 extends from the front end of the housing 10 toward the rear thereof, its length being determined by the amount the plunger 15 is desired to project beyond the boss 12 when in locked position. A flat spring 23 is attached at the forward end of the housing 10 and extends rearwardly therein, approximately the length of the offset 21, its rear portion being bent downwardly. The spring 23 is located so that it may fit within the offset 21, and hence not interfere with the movement of the fixed collar 16 when the latter is moved toward the rear of the housing 10. The rear or free end of the spring 23 is preferably turned upwardly slightly, and in that case, an aperture 22 is provided in the rear end of the offset 21 to receive this upturned end when the spring is flattened.

In operation, assuming the plunger 15 is in the position indicated in Fig. 4, the head 17 is pushed inwardly, causing the fixed collar 16 to move to the rear and force the flat spring 23 upwardly into the offset 21 and opening 22 (if provided). The floating collar 18, urged by the spring 19, will remain in its normal position at the front of the housing 10 during this initial movement of the plunger 15; and when the fixed collar 16 has passed the rear end of the flat spring 23, the latter snaps down and prevents the plunger 15, under the urging of the coiled spring 20, from returning to its former position. At this point, the mechanism is in the position indicated in Fig.

1, with the plunger 15 extending part way into a lock opening 24, which may be provided with a metal lining 25, in the other relatively movable member to be bolted. To release the bolt, the 5 head 17 is pushed farther into the housing 10, carrying with it the floating collar 18, the latter forcing the spring 23 up into the offset 21 to permit the collar to slide past. When the position indicated in Fig. 2 is reached, the finger is removed from the plunger head 17, and the plunger 15, under the urging of the spring 20, moves toward the front of the housing 10, the floating collar 18 remaining in its position by reason of the spring 23 bearing against its side and pressing 10 it against the opposite side of the housing, as shown in Fig. 3. As the fixed collar 16 moves forward, it meets the floating collar 18 and carries it forward, the latter preventing the spring 23 from springing down and stopping the fixed 15 collar. As soon as the floating collar 18 is carried past the flat spring 23, the former, under the urging of the spring 19, immediately snaps forward to its position against the face plate 13 and the plunger 15 follows it to the position shown in 20 Fig. 4, ready for another cycle of operations.

While we have shown a preferred form of our invention as it may be applied to the bolting of windows, it will be apparent that the same mechanism may be applied with no modification or 25 with slight modifications to doors, switches, valves, etc., wherever, in fact, a simple and easily-operated device for effecting this type of motion is desired. While we have illustrated and described a preferred form of our invention, we 30 wish it to be understood that our invention is not to be limited to the specific form or arrangement of parts herein described and shown, or specifically covered by our claims.

We claim as our invention:

40 1. A mechanism of the class described which includes: a housing; a plunger within said housing; a fixed collar on said plunger; spring means urging said collar forwardly in said housing; a head on the front end of said plunger; a floating collar on said plunger between said fixed collar and said head; a second spring means urging said floating collar toward said head; restraining means to prevent said floating collar from passing out of said housing; and a third spring means adapted to engage said fixed collar when 45 it has been moved rearwardly and prevent said first spring means from moving said plunger forwardly.

50 2. A mechanism of the class described which includes: a housing; a constriction at the rear end of said housing; a centrally-disposed outwardly-extending boss on said constriction; a plunger slidably mounted in said housing and adapted to extend through said boss; a fixed 55 collar on said plunger; an enlarged head on the front end of said plunger; a floating collar slidably mounted on said plunger between said fixed collar and said head; a spring urging said floating collar toward said head; a second spring urging said fixed collar toward the forward end

of said housing; an offset in one side of said housing extending from the front of said housing toward the rear of said housing; a flat spring adapted to fit in said offset and engage said fixed collar when said plunger has been moved to a 5 rearward position and prevent said plunger from moving toward the front of said housing under the urging of said second spring; and a face plate attached to the front of said housing, having an aperture therein large enough to permit said 10 plunger head to pass therethrough, but not large enough to permit said floating collar to pass through.

3. A mechanism of the class described which includes: a housing; a plunger within said housing; means for holding said plunger in a position partially extended from said housing; and a floating collar on said plunger adapted to disengage said holding means to thereby release 15 said plunger.

4. A mechanism of the class described which includes: a housing; a plunger within said housing; a collar fixed to said plunger; means adapted to engage said collar and hold it and said plunger in a position partially extended from said housing; and a floating collar on said plunger adapted to disengage said holding means from said fixed 20 collar to release said plunger.

5. A mechanism of the class described which includes: a housing; a plunger within said housing; a spring urging said plunger forward within said housing; means for holding said plunger in a position partially extended from said housing against the action of said spring; and a floating collar on said plunger adapted to disengage said 30 holding means to thereby release said plunger.

6. A mechanism of the class described which includes: a housing; a plunger within said housing; a collar fixed to said plunger; a spring urging said plunger forward within said housing; means adapted to engage said collar and hold it and said plunger from returning to normal position when said plunger is moved beyond a predetermined point in said housing against the action of said spring; and a floating collar on 40 said plunger adapted to disengage said holding 45 means from said collar.

7. A mechanism of the class described which includes: a housing; a plunger within said housing; means for holding said plunger in a position partially extended from said housing; and slideable means within said housing operated by movement of said plunger to disengage said plunger holding means and thereby release said plunger.

8. A mechanism of the class described which includes: a housing; a plunger within said housing; a collar fixed to said plunger; means adapted to engage said collar and hold it and said plunger in a position partially extended from said housing; and slideable means within said housing operated by movement of said plunger to disengage said plunger holding means and thereby release said plunger.
